TEXTILE SPINDLE

Elliot G. Crawford, Stonington, Conn., assignor to
William Triant, Arlington, Mass.

Application October 15, 1945, Serial No. 622,313

6 Claims. (Cl. 57—135)

1

This invention relates to a textile spindle such as is commonly employed on twisters.

The primary object of the invention is to improve the running qualities of the spindle and reduce wear to a minimum.

Among its features my invention embodies a spindle case having heat radiating fins and a whirl on the spindle and encircling the heat radiating fins of the spindle case so that as the whirl is driven to rotate the spindle a draft of air will be created over the heat radiating fins to cool the spindle case and spindle.

Other features include a single ball thrust bearing against which the bottom end of the spindle runs.

Referring to the drawings:

Figure 1 is a side view of a textile spindle embodying the features of this invention.

Figure 2 is a top plan view of the spindle illustrated in Figure 1.

Figure 3 is a bottom plan view of the spindle.

Figure 4 is a vertical sectional view showing certain portions in elevation to more clearly illustrate the details of construction.

Figure 5 is a vertical sectional view through the spindle.

Figure 6 is a transverse sectional view taken substantially on the line 6—6 of Figure 5, and

Figure 7 is a transverse sectional view taken substantially on the line 7—7 of Figure 5.

Referring to the drawings in detail, a spindle case designated generally 10 comprises a shank 11 having a screw threaded end 12 for the reception of a nut 13 by means of which the spindle case is clamped to a spindle rail against a flange 14 formed on the spindle case body intermediate its ends. That portion of the spindle case body 15 which projects above the flange 14 is provided with annular heat radiating fins 16. Opening through the upper end of the spindle case is a bore 17 which is provided adjacent its upper end with an enlarged bore 18 forming the upper bearing in the spindle case in which the spindle, to be more fully hereinafter described, runs. The lower end of the bore 17 communicates with a tapered bore 20 extending almost to the bottom end of the spindle case and seated at the extreme lower end of the bore 20 is a bearing ball 21.

Rotatably mounted in the bearing 19 is a bearing collar 22 of a spindle blade 23, the lower end of which projects into the bore 17 and is provided with a conically tapered portion 24 for entry into the conical bore 20 previously described. The lower end of the conical extension 24 rests

2

upon the ball 21 to provide for downward thrust of the spindle blade 23 as will be readily understood upon reference to Figure 5. Carried by the spindle blade 23 immediately above the upper end of the extension 15 of the case 10 is a whirl designated generally 25 which comprises a cylindrical body 26 carrying at its lower end an outwardly extending annular flange 27 and at its upper end a hub 28 which is attached to the spindle blade by a drive fit so that when the whirl is rotated the spindle blade will be rotated in unison therewith. As shown the upper end of the hub 28 is formed with a pad or seat 29 the upper surface of which rises above the general level of the hub 28 so that when a bobbin is mounted on the upper end of the whirl it will be held in spaced relation to the hub. Formed at the junction of the side walls 26 of the whirl and the hub 28 are upwardly and outwardly extending passages 30 the purpose of which will more fully hereinafter appear. The lower end of the whirl is spaced from the upper surface of the flange 14 as will be readily appreciated upon reference to the drawings.

25. In operation it will be understood that as the whirl 25 is rotated the spindle blade 23 will rotate in unison therewith and due to the rapid motion of the passages 30 a draft of air will be drawn upwardly between the heat radiating fins 16 and the inner face of the wall 26 of the whirl and discharged outwardly through the passages 30, thus effecting a cooling of the spindle.

While it is perfectly possible to cool the spindle as previously described, I find it advantageous to enclose the fins 16 in a suitable sleeve 31 which is of a diameter to avoid contact with the fins so as to permit the free flow of air upwardly and around the heat radiating fins. This sleeve is provided adjacent its upper and lower ends with annular rows of openings 32 and 33 respectively. These openings are to provide ventilation so that as the air is drawn upwardly by the rapid rotation of the openings 30 in the whirl 25 it will enter the passages 32 at the bottom of the sleeve 31 and pass upwardly over the fins 16 and then outwardly through the passages 32 at the top of the sleeve to be discharged through the openings 30 in the whirl. As previously stated such a sleeve or thimble is not essential to the operation 40 of the device but it does serve to improve the appearance of the case 11 when the spindle and whirl have been removed therefrom.

While in the foregoing there has been shown and described the preferred embodiment of this invention it is to be understood that minor

changes in the details of construction, combination and arrangement of parts may be resorted to without departing from the spirit and scope of the invention as claimed.

What I claim is:

1. In a textile spindle, a spindle case adapted to be mounted on a spindle rail, a spindle mounted in the case to rotate about a vertical axis, and a whirl on the spindle, said whirl surrounding the spindle case and having an annular row of outwardly inclined openings in its upper end to create a draft of air upwardly between the spindle case and the whirl as the whirl rotates the spindle.
2. In a textile spindle a spindle case adapted to be mounted on a spindle rail, heat radiating fins on the spindle case, a sleeve encircling the heat radiating fins and means to create a draft of air through the sleeve and over the fins to cool the spindle case.
3. In a textile spindle a spindle case adapted to be mounted on a spindle rail, heat radiating fins on the spindle case, a spindle mounted in the case to rotate about a vertical axis and means operable upon rotation of the spindle to create a draft of air over the fins to cool the case.
4. In a textile spindle a spindle case adapted

to be mounted on a spindle rail, heat radiating fins on the spindle case, a spindle mounted in the case to rotate about a vertical axis, a sleeve encircling the heat radiating fins and means operable upon rotation of the spindle to create a draft of air through the sleeve and over the fins to cool the case.

5. In a textile spindle a spindle case adapted to be mounted on a spindle rail, heat radiating fins on the spindle case, a spindle mounted in the case to rotate about a vertical axis, a whirl on the spindle and enclosing the heat radiating fins, said whirl having spaced openings in its upper end which serve to create a draft of air over the fins to cool the case.

10 6. In a textile spindle a spindle case adapted to be mounted on a spindle rail, heat radiating fins on the spindle case, a thrust ball in the spindle case, a spindle resting on the ball and rotatable in the case about a vertical axis, a spindle blade at the upper end of the spindle, a whirl on the spindle, said whirl encircling the heat radiating fins and having an annular row of spaced openings at the junction of its top and side walls whereby when the whirl is driven a draft of air 15 20 25 will be created over the fins to cool the case.

ELIOT G. CRAWFORD.
